UNITED STATES PATENT OFFICE.

WILLIAM H. STINSON, OF MOUNT VERNON, NEW HAMPSHIRE.

DESIGN FOR A BADGE.

SPECIFICATION forming part of Design No. 17,390, dated June 14, 1887.

Application filed April 14, 1887. Serial No. 234,841. Term of patent 7 years.

To all whom it may concern:

Be it known that I, WILLIAM H. STINSON, a citizen of the United States, residing at Mount Vernon, in the county of Hillsborough and 5 State of New Hampshire, have invented and produced a new and original Design for a Badge-Pin, of which the following is a specification, reference being had to the accompanying drawing, forming part thereof.

10 The figure in the drawing represents a badge in the shape of a shield, in the middle of which is a circular "field," on which is displayed a sheaf of wheat "statant," with a band around it, and a sickle. Around this field is a circle, and outside of the circle are seven stars equi- 15 distant from each other. At the top of the shield is a "right" segmental panel, and at the bottom of the shield is a "reverse" seg- mental panel.

20 The leading features of this design for a

badge consist in the shield-shaped body having thereon the sheaf of wheat statant, surrounded by the band and with a sickle, and the surrounding circle and the seven stars.

What I claim is—

25 The design of a badge herein shown and de- scribed, the same consisting of the shield- shaped body having on it the sheaf of wheat statant, the band and sickle, the circle sur- rounding the central portion, the seven stars, 30 and the upper and lower panels, all as de- scribed.

In testimony that I claim the foregoing as my own I have hereto affixed my signature in presence of two witnesses.

WILLIAM H. STINSON.

Witnesses:

MABEL SOUTHWARD,
EDWARD J. JONES.
